[57] **CLAIM**

The ornamental design for the optical magnetic disc player combined with radio receiver and tape recorder, as shown and described.

DESCRIPTION

FIG. 1 is a front perspective view of the optical magnetic disc player combined with radio receiver and tape recorder in accordance with the present invention;

FIG. 2 is another front perspective view thereof, showing the disc player and tape recorder in an open position; the undisclosed inside views of the optical magnetic disc player combined with radio receiver and tape recorder form no part of the claimed design;

FIG. 3 is another front perspective view of the optical magnetic disc player combined with radio receiver and tape recorder shown in a using condition with the antenna partially withdrawn;

FIG. 4 is a front elevation view of the optical magnetic disc player combined with radio receiver and tape recorder of FIG. 1;

FIG. 5 is a rear elevation view of the optical magnetic disc player combined with radio receiver and tape recorder of FIG. 1;

FIG. 6 is a left side elevation view of the optical magnetic disc player combined with radio receiver and tape recorder of FIG. 1;

FIG. 7 is a right side elevation view of the optical magnetic disc player combined with radio receiver and tape recorder of FIG. 1;

FIG. 8 is a plan view of the optical magnetic disc player combined with radio receiver and tape recorder of FIG. 1; and,

FIG. 9 is a bottom plan view of the optical magnetic disc player combined with radio receiver and tape recorder of FIG. 1.
